ATOMIZER

Charles A. Fortin, Montreal, Quebec, Canada, assignor to Institution Catholique des Sourds-Muets Pour la Province de Quebec, Montreal, Quebec, Canada, a corporation of Quebec

Application August 8, 1949, Serial No. 109,109
In Canada July 28, 1949

7 Claims. (Cl. 299—88)

1

Introduction

This invention relates to an atomizer, particularly one adapted for pocket use for dispensing perfume.

A type of atomizer to which the present invention may be applied is disclosed in U. S. design Patent application D. 13,095, May 17, 1947, now Design Patent No. 155,683, Albert J. Bruneau, U. S. patent application, 684,426, July 18, 1946, now Patent No. 2,543,829, Albert J. Bruneau, and U. S. patent application Serial No. 792,228, now Patent No. 2,563,231, December 17, 1947, Charles A. Fortin.

The device as shown in these patents and application are ideal for the purpose, but the present invention aims to provide certain improvements which permit greater ease in manufacturing and also better operation.

Having regard to the foregoing, the present invention contemplates an atomizer of the following construction. It includes a body formed with first and second spaced-apart chambers each extending from one end of the body to adjacent the other and a transverse passageway leading from the chambers to a dispensing outlet on a face of the body. The first chamber extends from one end of the body across the transverse passageway thus having portions at both sides of this passageway. Thus the transverse passageway normally leads directly into and through the first chamber. A first tube is located in the transverse passageway and extends from a point between the two chambers to the outlet forming an air passage between the second chamber and the outlet. A second tube larger than the first tube is located in the passageway and surrounds the first tube. Preferably the tubes are cylindrical and concentric. The second tube extends from a point between the first chamber and the outlet so as to form between it and the first tube a liquid passage leading from the first chamber to the outlet. The ends of the two tubes are co-extensive and form therebetween a liquid outlet, while the first tube forms an air inlet concentric with the liquid outlet. The inner end of the second tube forms between it and the first tube a liquid inlet having access at all sides of the first tube to the chamber. Adjustable means is provided for controlling the liquid outlet. This means preferably include a cap having a skirt threadably engaging the outside of the second tube. The cap includes an opening adapted to register with the above-mentioned air opening. The inside of the cap is provided with a washer

adapted to overlie the ends of the first and second tubes and so the liquid outlet formed therebetween. The second chamber includes a pump for forcing air through the air communication and outlet so as to aspirate liquid from the liquid communication.

In one embodiment of the invention, the first chamber has an opening on the surface of the body at the end remote from the transverse passageway and this opening is provided with a removable closure. In another embodiment of the invention the first chamber has an opening on the surface of the body at the end nearest the transverse passageway and this opening is provided with a removable closure.

According to a further embodiment of the invention there is a first tubular member mounted within the transverse passageway and extending through the outlet end thereof to a point beyond said first chamber. This tube has a fixed cap on its outer extremity having an orifice therein constituting a dispensing opening. A passage-forming member is adjustably mounted within the passageway, for example by the passageway being tapped and the passage-forming member being threaded, this member extending from a point adjacent the cap to a point on the opposite face of the body.

This member is provided with an opening extending from the outlet end to a point beyond the second passageway and is provided with a portion of reduced diameter extending from the end adjacent the opening to a point normally beyond the second passageway. The tube and passage-forming members are also provided with openings adapted to communicate with the first and second chambers. The end of this member adjacent the outlet is adapted in certain positions to bear against the underside of the cap and in other positions to clear the cap to form a liquid channel. The member is provided with a head on its other end whereby it can be rotated to bring the head against the cap for sealing the liquid opening or to adjust the clearance for dispensing. The member is formed with an opening leading from its bore to the second chamber. The second chamber contains the air pump.

According to a modification of this structure, the passage-forming member includes an annular outside washer adjacent the end remote from the outlet to prevent escape of liquid from said second chamber. In accordance with a still further refinement of the invention the outlet end of the passage-forming member is provided with a 55 perforated nose of resilient material adapted to

seat on the nozzle of the cap and a central vent tube projecting beyond its end.

Detailed description

Having thus generally described the nature of the invention, it will be described in more detail by reference to the accompanying drawings illustrating an atomizer according to preferred embodiments, and in which:

Figure 1 is a perspective view of an atomizer according to one of these embodiments.

Figure 2 is a vertical cross section through the atomizer shown in Figure 1 with the sleeves and closure cap shown in elevation.

Figure 3 is an enlarged vertical cross section of the atomizer shown in the previous two figures with the pump plunger drawn out.

Figure 4 is a fragmentary vertical cross section through an atomizer of similar construction to that of the previous figures, but modified in certain respects.

Figure 5 is a vertical fragmentary cross section showing a modification of the atomizer shown in the previous figures.

Figure 6 is a vertical cross section of another embodiment of atomizer according to the invention.

Figure 7 is an enlarged vertical cross section showing the atomizer of the previous figure.

Figure 8 is a fragmentary cross section showing the structure of the nozzle and passage-forming member of the atomizer of Figures 6 and 7.

Figure 9 is a vertical fragmentary cross section showing a modification of the nozzle structure of Figure 8.

Figure 10 is a transverse vertical cross section of the nozzle structure of the atomizer of the previous figure.

Referring more particularly to the drawings, Figure 1 shows one preferred form of atomizer according to this invention. In this preferred form the body of the atomizer 11 is made up of a unitary block of material for example, metal, say an aluminum alloy, which is drilled to form a pair of chambers 15 and 20, and a transverse passage 25. The chamber 20 is connected to the passage 25 by an opening 27. The chamber 15 has a portion 28 of restricted size extending upwards through and beyond the transverse passage 25. The body is formed with a diagonal corner as at 30.

Within the transverse passage is mounted a sleeve 35 which is provided with a widened portion 26 which fits in a widened portion in the passage 25. The narrow portion of the sleeve 35 extends forwardly and projects beyond the diagonal face of the body. An outer sleeve 40 is mounted in the passage 25 concentrically with the sleeve 26. There is formed between the inner and outer sleeves 26 and 40 a passage 42. The sleeves 40 and 26 have co-extensive ends 41 and 29 respectively. The end of the inner sleeve 26 is provided with a vent tube 45 which projects beyond the end of the sleeve 26. Mounted on the end of the sleeve 40 preferably by screw threading is a cap 50 which has a side skirt 52 which engages the sleeve 40, and a cap portion 54. The cap portion 54 is provided with an opening 55 forming the dispensing opening of the nozzle. A washer 60 is mounted within the cap 50. The washer is provided with a centrally-arranged opening 61 registering with the opening 55 in the cap 50. The rear end of the transverse channel 25 is provided with a plug 57. A suitable closure 70 is provided in the chamber 15 and a pump 71 is provided in the chamber 20.

Operation

In operation the body of the atomizer is inverted from the position shown in the drawings and the plunger is reciprocated which forces air through the channel 25 and out through the air vent 55. The passage of air from this air vent and the opening 41 aspirates perfume from the chamber 15 and then out through the passageways between the sleeves 26 and 40 and out between the sleeve 26 and washer 47, then out through the opening in the cap.

As will be noted, the extension of the chamber 15 to above the tube 26 and the starting of the tube 40 within the chamber 15 permits ready access to the fluid of the passage between the members 26 and 40. When the body of the atomizer is inverted, the fluid tends to feed by gravity through the fluid passageway and is readily aspirated from the dispensing opening by air forced from the air channel.

First alternative structure

In the alternative structure shown in Figure 4 the numbers of the respective parts are similar with the exception that they have been raised by one hundred. The structure of the atomizer is similar with the exception that there is no recess or diagonal portion 30 on the body and the chamber 115 is of substantially the same diameter throughout its length. The portion of the chamber 115 extending above the sleeve 126 is of the same diameter as the lower portion of the chamber.

The operation of this form of the device is similar to that of Figure 1.

Second alternative structure

In the alternative form illustrated in Figure 5 two hundred has been added to the numbers of each of the parts and the parts are similar. This form differs from that of Figure 2 in that the closure 270 for the chamber 215 is at the top of the atomizer instead of at the bottom, the chamber 215 having been formed by drilling the body from the top instead of the bottom. The operation is the same as in the previous figures.

Third alternative form

The form of the device illustrated in Figures 6 through 9 is somewhat different although the principle of operation is the same. In the transverse passage there is mounted a fixed cap member 345 provided with a dispensing opening 341. In the transverse passage which is tapped there is mounted a threaded tube 326. This tube is provided with a narrow portion 328 which forms between itself and the cap 341 a perfume channel leading from the perfume chamber 315 to the outlet in the cap 341. The threaded tube 326 is provided with a knurled head 350 whereby the tube can be turned and thus moved forward or backward in respect of the cap 341. In this manner the washer on the end of the tube is brought into contact with the cap or retracted from contact with the cap, thus either closing off the perfume passage or leaving a passage of adjustable size as the case may be.

The tube 326 is provided with an opening 355 which is adapted to register with the opening 327 leading from the air chamber to the inside of the tube 326. The cap member 345 is provided with an opening 370 leading from the chamber 315 so that liquid can run from the chamber 315 into the passage formed between

the cap member 345 and narrow portion 328 of the passage-forming member.

The operation in dispensing is similar to the device of the other figures.

Other forms

In Figure 8 is illustrated a slightly different form of tube insertable in the transverse channel of the atomizer. The internal opening in the tube is drilled from the front and there is an insert bushing 480 which carries the air vent. A rubber safety joint or sleeve 428 may be located in an annular groove in the wall of the tube adjacent to the head. The purpose of this sleeve is to prevent leakage of air from the pump.

Figure 9 shows an alternative form of nozzle capable of being used particularly with the form of the invention shown in Figure 8. Figure 9 shows a variation of the structure shown in Figure 8. The end of the passage-forming member is provided with an insert 580 which carries the vent tube 581. Mounted on the vent tube and flush against the passage-forming member is a washer 585 of resilient material adapted to seat against the inside of a cap like the cap 345 of Figure 7.

Figure 10 is a transverse vertical cross section through a nozzle like that of Figure 8.

I claim:

1. An atomizer of the type including a body formed with a pair of spaced-apart chambers constituting a liquid containing chamber and a pump chamber extending from one end of the body to adjacent the other and a transverse passageway leading from the chambers to a dispensing outlet, wherein the chamber closest to said outlet extends to a point above the transverse passageway so that the transverse passageway extends through the chamber, and means in the transverse passageway extending from a point between said chambers to a point adjacent to said outlet forming a centrally-arranged air passage connected to the chamber remote from said outlet and extending past said other chamber without connection thereto, means in said transverse passageway extending from a point between said closest chamber and said outlet to a point adjacent to said outlet forming between it and said first means a liquid passageway leading from said liquid containing chamber to said outlet, and adjustable means for controlling the egress of liquid from the outlet.

2. An atomizer, according to claim 1, wherein the said liquid containing chamber has an opening on the surface of said atomizer body at the end remote from said transverse passageway and is provided with closure means at that end.

3. An atomizer, according to claim 1, wherein the said liquid containing chamber opens on the surface of the body at the end adjacent to the transverse chamber and is provided with closure means at that end.

4. An atomizer of the type including a body formed with a pair of spaced apart chambers constituting a liquid containing chamber and a pump chamber extending from one end of said body to adjacent the other and a transverse passageway leading from the chambers to a dispensing outlet, wherein the chamber closest to said outlet extends to a point above the transverse passageway so that the transverse passageway extends through the chamber, an internal tube extending within said transverse passageway from a connection with said pump chamber to said outlet without connection to said liquid chamber to constitute a centrally arranged air passage, an external tube concentric with the internal tube and extending within said passageway from a point adjacent to the liquid chamber to said outlet forming between it and said internal tube a liquid passageway leading from said liquid containing chamber to said outlet, and adjustable means for controlling the egress of liquid from the outlet.

5. An atomizer according to claim 4, wherein said transverse passageway is provided with a widened portion adjacent said outlet and said adjustable means comprises a cap mounted on said outer tube for rotary axial movement and having a portion extending within said passageway widened portion.

6. An atomizer according to claim 4, wherein the said liquid containing chamber has an opening on the surface of said atomizer body at the end remote from said transverse passageway and is provided with closure means at that end.

7. An atomizer according to claim 4, wherein the said liquid containing chamber opens on the surface of the body at the end adjacent to the transverse chamber and is provided with closure means at that end.
